SIPHONIC CIRCULATING APPARATUS

Filed Aug. 15, 1929

George T. ^{INVENTOR} Brout,
C. W. Miles,
ATTORNEY

UNITED STATES PATENT OFFICE

GEORGE T. PROUT, OF COVINGTON, KENTUCKY

SIPHONIC CIRCULATING APPARATUS

Application filed August 15, 1929. Serial No. 386,188.

My invention relates to improvements in steam generating boilers, particularly locomotive boilers. One of its objects is to provide improved apparatus to promote an active circulation of water within the boiler.

Another object is to protect the crown sheet of the boiler from injury. Another object is to increase the fuel efficiency. Another object is to increase the boiler efficiency per unit of heating surface. Another object is to provide improved siphonic means to promote an active and correct flow and circulation of water in the boiler and which is strong and reliable and adapted to pass a large volume of water and thereby prevent excessive heating or burning at any locality of the siphonic means or members. Another object is to provide improved siphonic circulating means which is mutually supporting and practically free from unequal strains, or locally excessive strains, or to unequal strains due to uneven heating. My invention also comprises certain details of form and arrangement and combination of components, all of which will be fully set forth in the description of the accompanying drawings, in which:

Fig. 1 is a central vertical section through the fire-box and a portion of the boiler of a locomotive showing my improvements applied thereto, being a section on line 1—1 of Fig. 2.

Fig. 2 is a vertical section through the same taken on line 2—2 of Fig. 1.

Fig. 3 is a perspective view of the crown sheet and one of the side plates detached.

Fig. 4 is a perspective view of one of the siphonic water circulating members detached.

Fig. 5 is a section taken on line 5—5 of Fig. 1.

In steam generating boilers, particularly locomotive boilers, where it is desirable to generate relatively large volumes of steam in a limited period of time, it is desirable and important to secure a relatively strong and active circulation of the water in the boiler in order to bring the cooler portions of the water into contact with the heated boiler plates, and thereby effect a rapid transfer of heat to the water, and prevent local develop-
ment of water vapor in contact with the heated plates to an extent to prevent access of water to the heated plate until the plate becomes overheated or burned. It is also important to provide for the circulation of relatively large volumes of water in contact with the crown sheet, siphonic members, and all parts of the boiler plates in intimate contact with the highly heated gases of the fire box. It is also important to so arrange the siphonic members and parts exposed to direct contact with the highly heated gases of the fire box that they may have and retain a maximum strength and not be subjected to local excessive strains due to changes in temperature or zones of relatively different temperature. In apparatus heretofore employed the local concentration of heat in the fire box combined with a restricted circulation of water in the boiler was liable to cause excessive local heating and burning of the plates and boiler members.

The accompanying drawings illustrate one embodiment of my invention in which 15 represents the sheath or outside boiler plate 75 of a locomotive boiler, 16 represents the crown-sheet, 17 represents the rearward flue sheet, 18 the flue tubes, 19 the fire box, 20 the fire box doorway, and 21 the fire box door. The fire box is shown as being heated by 80 means of a fluid fuel burner 22, but may be fired by means of coal or other solid fuel if desired. The outside plate 15 and the crown sheet 16 are brought down upon both sides and on the front of the fire box so as to form 85 water legs or jacket spaces 23 substantially surrounding the fire box.

In order to promote a rapid and vigorous circulation of water in the boiler and including these water jacket spaces 23, substantially 90 as indicated by the arrows in Fig. 1, I provide two siphonic members 24, each of which comprises a substantially vertical element or circulating channel 25, and a substantially horizontal element or circulating channel 26, 95 which circulating channels 25 and 26 unite at substantially right angles to form an L-shaped circulating channel leading horizontally in from a water jacket space 23 at the side of the fire box and thence upwardly 100

through a vertically directed section and leading into the boiler space above the crown-sheet. Both the horizontal section 26 and the vertical section 25 of the circulating channels are exposed on all sides to the highly heated gases of the fire box, and said circulating channels are relatively so ample, short, and unobstructed as to be able to carry and circulate such large volumes of water as to prevent an accumulation or pocket of steam or water vapor at any locality where the plate could become overheated or burnt. The horizontal sections 26 are curved and inclined in cross section, and thereby provide not only for a circulation of water horizontally toward and through the vertical sections 25, but they also provide for a transverse circulation of any water in excess of what may be taken up through the vertical section 25, this transverse circulation being directed from the lower end of the water jacket space 23 into the lower end of the section 26 and thence toward the upper end of section 26 and out into the upper portion of the water jacket space 23 and up over the crown-sheet. The flow of water through the sections 25 and 26 provides an ample supply and flow of water over all portions of the upper face of the crown-sheet thereby preventing excessive heating of the crown-sheet. The channels 26 also draw in from the forward and relatively cooler flue portion of the boiler through the open ends 28 of sections 26 a supply of water to be circulated upwardly through either the sections 26 and 25, or through the sections 26 alone to a position above the crown-sheet.

The siphonic members are adapted to be formed from two sheet metal plates 31 and 32, united by welded joints along the meeting edges of said plates. The siphonic members are right hand and left hand counterparts one of the other and each have two flanges 35, and 36. The flanges 35 are attached by rivets or welds to the top of the crown-sheet 46 to register with perforations 38 through the crown-sheet. The flanges 36 are attached to the sides of the crown-sheet to register with perforations 30 through the sides of the crown-sheet. The edges 37 are not flanged but are attached by lap-welds to the rear flue sheet 17 below the flue tubes to register with the flanges 52 of perforations 40 through the rear flue sheet. The siphonic members 24 are stayed by means of a series of stay bolts 42. Additional stay rods may be employed whenever required to strengthen the structure. The L-shape of the siphonic members, and the three points of attachment thereof to the boiler render said siphonic members and their attachment joints particularly strong and rigid and self supporting, and free from strains due to the changes in temperature or irregular local changes of temperature. The curved portions 54 at the junctions of the sections 25 and 26 serve to compensate for ex-

pansion. Corrugations or curved outlines 53 are given to the flue sheet 17 adjacent to the perforations 40, which are greater at the center of the sheet 17 and taper out to a practically plane face near the edges of the sheet 17 as shown in Fig. 5. These corrugations 53 materially assist in compensating for expansion and contraction of the adjacent metal. Apertures 46 and 47 on opposite sides of the door frame 20, serve as stoker holes or as poker holes. A series of tiles 68 bridge a portion of the space between the siphonic members and rest upon the curved portions 54. The meeting edges of the tiles are beveled to prevent the tiles being fused together. 70 75 80

The apparatus herein shown and described is capable of considerable modifications within the scope of the claims without departing from the spirit of my invention. 85

What I claim is:

1. In a locomotive boiler fire box having a crown, side water legs and flue sheet; a siphonic member applied thereto, said member comprising vertical and bottom sections substantially coextensive and providing water spaces disposed in substantially L-shaped relation, the said bottom section having its lower and upper walls arranged parallel and curved upwardly from front to rear, the said bottom section communicating at its front end with the lower part of said flue sheet and at one side with said leg in an upwardly curving direction, said section being in communication with said leg throughout substantially the entire height thereof, and the upper end of said vertical section communicating with said crown sheet. 95 100 105

2. In a locomotive boiler fire box having a crown, side water legs and flue sheet a siphonic member applied thereto, said member comprising vertical and bottom sections substantially coextensive and providing water spaces disposed in substantially L-shaped relation, the forward end of said vertical section being concave, the said bottom section having its lower and upper walls arranged parallel and curved upwardly from front to rear, the said bottom section communicating at its front end with the lower part of said flue sheet and at one side with said leg in an upwardly curving direction, said section being in communication with said leg throughout substantially the entire height thereof, and the upper end of said vertical section communicating with said crown sheet. 110 115 120

In testimony whereof I have affixed my signature.

GEORGE T. PROUT.
